HYDROCARBON CONVERSION

Edwin H. McGrew, Chicago, Ill., assignor to Universal Oil Products Company, Chicago, Ill., a corporation of Delaware

Application August 21, 1939, Serial No. 291,193

2 Claims. (Cl. 196—52)

This invention relates to a process for converting hydrocarbon oils into substantial yields of gasoline of high octane rating, relatively low olefin content, and a low potential gum content. More specifically, it relates to a process which involves a series of concomitant steps combined in a novel and advantageous manner so that they cooperate to produce the desired results.

The invention involves principally thermal cracking treatment of a heavy hydrocarbon oil, such as, for example, reduced crude, high temperature catalytic cracking treatment of a lighter hydrocarbon oil, such as gas-oil, low temperature catalytic cracking treatment of the gasolines produced in the thermal cracking and the high temperature catalytic cracking treatments in commingled state with light reflux condensate formed in the thermal cracking treatment to produce a gasoline of high octane rating and relatively low olefin content.

The term "high temperature catalytic cracking treatment" as used throughout the specification and claims refers to the treatment of hydrocarbon oils in the presence of catalytically active masses at temperatures ranging, for example from 800 to 1200° F. and at pressures varying from substantially atmospheric to 200 pounds or more per square inch whereby to effect substantial conversion to gasoline boiling range hydrocarbons. The term "low temperature cracking treatment," on the other hand, refers to the treatment of gasoline boiling range hydrocarbons at relatively low temperatures, in a more limited sense, however, it refers to the treatment of gasoline boiling range hydrocarbons in commingled state with light recycle formed in the thermal cracking treatment in the presence of catalytically active masses of a similar character to those employed in the high temperature catalytic cracking treatment at temperatures ranging, for example, from 600 to 900° F. and at a pressure ranging from substantially atmospheric to 200 pounds or more per square inch whereby to effect a transfer of hydrogen from the heavier hydrocarbons of the recycle to the lighter olefinic hydrocarbons which are contained in the gasoline thereby producing a gasoline of substantially the same boiling range and at the same time containing a greater percentage of saturated aliphatic hydrocarbons.

The gasolines from thermal cracking and from high temperature catalytic cracking ordinarily contain a relatively high percentage of olefinic hydrocarbons which tend to increase the octane number of the gasolines to some degree. However, due to their potential gum forming proper-

ties and because the gasolines that contain high percentages of olefinic hydrocarbons have a relatively high acid heat test and a relatively low susceptibility to added antiknocking agents, these 5 gasolines cannot be used as an aviation fuel. On the other hand, gasolines which are predominantly paraffinic and which may also contain aromatic hydrocarbons, and which, in addition, contain relatively large amounts of isomeric paraffinic compounds, are particularly useful as an aviation gasoline because of the low acid heat test and good susceptibility to added antiknocking agents, such as tetraethyl lead. It has been found 10 that when the gasolines produced in thermal cracking and high temperature catalytic cracking are subjected to contact with a catalytically active mass in commingled state with a light recycle from the thermal cracking operation, a hydrogen transfer is effected from the higher boiling hydrocarbons contained in the recycle oil to the lower hydrocarbons contained in the gasoline and that in addition isomerization and 15 cyclization may take place to form a gasoline which contains high percentages of aromatic hydrocarbons and in addition has a high octane rating and good susceptibility to antiknocking agents.

It is believed that in the low temperature catalytic cracking treatment that saturated hydrocarbons, and particularly the naphthenic hydrocarbons of the recycle oils act as hydrogen donors for the olefinic hydrocarbons of the gasoline, whereby the olefinic hydrocarbons become saturated to form paraffinic hydrocarbons and naphthenic hydrocarbons are converted to aromatic hydrocarbons. Various other reactions, such as, for example, dehydrogenation and cyclization of an aliphatic hydrocarbon to form an aromatic hydrocarbon with the formation of 2 to 3 molecules of hydrogen which attach to the unreacted olefinic hydrocarbons may also take place. However, since the invention is concerned primarily with a process in which the various reactions may be conducted, no further discussion is necessary 20 of what chemical reaction may possibly be involved in the low temperature catalytic cracking treatment.

In one specific embodiment the invention comprises subjecting a mixture of heavy reflux condensate, formed as hereinafter described, and a heavy hydrocarbon oil charging stock to thermal cracking treatment in a heating coil and communicating reaction chamber, supplying the resultant vaporous and liquid conversion products to a vaporizer and separator to separate the va-

porous conversion products from non-vaporous liquid residue, recovering the latter, fractionating said vaporous conversion products to form light and heavy reflux condensate and to separate fractionated vapors boiling in the range of gasoline, returning said heavy reflux condensate to the thermal cracking treatment, simultaneously commingling reflux condensates formed in a high temperature catalytic cracking treatment and in a subsequent low temperature cracking treatment with a light hydrocarbon oil, heating and vaporizing the mixture and subjecting the heated vapors to contact with a cracking catalyst in a high temperature cracking zone, fractionating the conversion products from said high temperature cracking zone to separate gasoline boiling range hydrocarbons from the higher boiling hydrocarbons, condensing the latter as reflux condensate and supplying it as aforesaid to the high temperature catalytic cracking treatment, subjecting said gasoline boiling range hydrocarbons to cooling and condensation and collecting the resulting distillate and gas, commingling the fractionated vapors from the thermal cracking treatment and the distillate from the high temperature catalytic cracking treatment with light reflux condensate from the thermal cracking treatment, heating the mixture and subjecting the heated oil to contact with a cracking catalyst in a low temperature cracking treatment, fractionating the conversion products from the low temperature cracking treatment to separate a gasoline product from the higher boiling hydrocarbons, recovering the former, condensing said higher boiling hydrocarbons as reflux condensate and returning it to the high temperature catalytic cracking treatment.

The accompanying diagrammatic drawing shows in conventional side elevation one specific form of the apparatus in which the object of the invention may be accomplished. It is to be understood that the invention is not limited to processing in the specific form of the apparatus herein disclosed and that various modifications of the process and apparatus herein described may be made without departing from the broad scope of the invention.

Referring now to the drawing, charging stock, preferably comprising a heavy hydrocarbon oil, such as, for example, reduced crude, is introduced through line 1 and valve 2 to pump 3, which discharges through line 4 and valve 5, the oil commingled with heavy reflux condensate, formed as herein described, and the mixture introduced to heating coil 6. The oil in passing through heating coil 6 is raised to the desired cracking temperature, which may range, for example, from 850 to 1000° F., and is maintained at this temperature for a sufficient period of time for substantial cracking to be effected, the heat for cracking being supplied by furnace 1. The heated conversion products leaving heating coil 6, at a superatmospheric pressure ranging, for example, from 200 to 600 pounds or more per square inch, are directed through line 8 and valve 9 into reaction chamber 10 wherein they are subjected to prolonged conversion at an elevated temperature. Reaction chamber 10 is preferably operated at a superatmospheric pressure substantially the same as that employed on the outlet of heating coil 6, and is preferably insulated to reduce radiation losses therefrom, although no insulation is shown in the drawing.

The vaporous and liquid conversion products leaving reaction chamber 10 are directed

through line 11 and valve 12 into vaporizing and separating chamber 13, which is operated at a substantially reduced pressure relative to that employed in reaction chamber 10, ranging, for example, from 50 to 250 pounds or more per square inch wherein the vaporous conversion products are separated and the liquid conversion products subjected to substantial further vaporization to form a non-vaporous liquid residue. Valve 12 is preferably a pressure control valve by means of which a substantial superatmospheric pressure is maintained on the heating coil and communicating reaction chamber after which the pressure is lowered to effect vaporization in chamber 13. The non-vaporous liquid residue separated in chamber 13 is directed from the lower portion thereof through line 14 and valve 15 to cooling and storage or elsewhere as desired.

The vaporous conversion products, together with the vapors evolved within chamber 13, are directed through line 16 and valve 17 into fractionator 18, which is preferably operated at a superatmospheric pressure of substantially the same magnitude as that employed in chamber 13. The vaporous products introduced to fractionator 18 are subjected to fractionation therein to form light and heavy reflux condensates and to separate fractionated vapors boiling in the range of gasoline. The heavy reflux condensate is directed from the lower portion of fractionator 18 through line 19 and valve 20 into pump 21 which discharges through line 22 and valve 23 into line 4 where the heavy reflux condensate commingles with the charging stock, as previously described.

Fractionated vapors separated in fractionator 18 are directed from the upper portion thereof through line 24, and, when desired, all of the vapors may be directed through valve 25 into cooler and condenser 26 wherein they are subjected to cooling and condensation. The distillate formed in condenser 26, together with undissolved and uncondensed normally gaseous hydrocarbons, is directed through line 27 and valve 28 into receiver 29 wherein the distillate and gases are collected and separated. Normally gaseous hydrocarbons collected in the upper portion of receiver 29 are directed therefrom through line 30 and valve 31 to collection and storage or to further treatment as desired. A portion of the distillate collected in receiver 29 may be returned to the upper portion of fractionator 18, by well known means not shown, as a refluxing and cooling medium therein. When desired, the balance of the distillate may be directed through line 32 and valve 33 and recovered as a product of the process. On the other hand, the distillate collected in receiver 29 may, when desired, be directed through line 34 and valve 35 to pump 36, which discharges through line 37 and valve 38 into line 82 for low temperature catalytic cracking treatment, as subsequently described.

However, since the thermal cracking treatment is ordinarily operated at a superatmospheric pressure equivalent to or in excess of that employed in the low temperature catalytic cracking treatment, it might be desirable as a means for conserving heat to introduce the fractionated vapors from fractionator 18 to the low temperature catalytic cracking treatment without prior condensation when the thermally cracked gasoline is subjected to low temperature catalytic cracking treatment. In this case, the portion of fractionated vapors in line 24, which is in excess of the amount required for refluxing the upper portion of fractionator 18, may be directed

through line 39 and valve 40 into line 82 for treatment, as subsequently described.

Simultaneously with the thermal cracking treatment of the heavy hydrocarbon oil, as previously described, a light hydrocarbon oil, such as, for example, kerosene or gas-oil, is introduced through line 41 and valve 42 to pump 43, which discharges through line 44 and valve 45, the oil commingling with reflux condensates formed in the high temperature and low temperature catalytic cracking reactions, as hereinafter described, and the mixture thereafter introduced to heating coil 46. The oil in passing through heating coil 46 is substantially completely vaporized therein and raised to the desired temperature, which may range, for example, from 800 to 1200° F. without substantial pyrolytic cracking thereof, the heat being furnished by furnace 47. The heated vapors leaving heating coil 46 at a pressure ranging, for example, from substantially atmospheric to 200 pounds or more per square inch, are directed through line 48 and valve 49 into reactor 50 wherein the vapors are subjected to contact with a cracking catalyst disposed therein while they are maintained at substantially the same temperature as that employed on the outlet of the heating coil by means of heat supplied from an external source whereby to effect substantial conversion into gasoline boiling range hydrocarbons.

The preferred cracking catalysts for use in the present process consist in general of a precipitated alumina hydrogel and/or zirconia hydrogel composited with silica hydrogel, the gel composite being washed, dried, formed into particles and calcined to produce a catalytic mass. It is not intended, however, that the process should be limited to these particular catalysts, for other catalysts, such as, for example, the hydrosilicates of alumina, acid treated clays, and the like, may be used within the broad scope of the invention.

In the following specification and claims the terms silica, alumina, silica-zirconia, and silica-alumina-zirconia masses are used in the broad sense to designate the synthetic composites referred to above. The preferred catalysts may be prepared by precipitating silica from a solution as a hydrogel within or upon which the alumina and/or zirconia are deposited also by precipitation as hydrogels. The silica hydrogel may conveniently be prepared by acidifying an aqueous solution of sodium silicate by the addition of a required amount of hydrochloric acid. After precipitating, the silica gel is preferably washed until substantially free from alkali metal salts. The washed silica hydrogel is then suspended in a solution of alumina and/or zirconium salts and an alkaline precipitant, such as ammonium hydroxide, ammonium carbonate or ammonium sulfide added to the solution to precipitate aluminum and/or zirconium hydrogels. The final precipitate, comprising essentially hydrated silica and hydrated alumina and/or zirconia, is washed to substantially completely remove water soluble materials and dried at about 300° F. to produce a rather crumbly and granular material which may be ground and pelleted or sized to produce particles of catalyst after which the catalyst particles are calcined at a temperature in the approximate range of 1000 to 1500° F. Various other procedures, such as, for example, coprecipitation of the hydrated gels may be employed, when desired, to produce the preferred catalyst.

Reactor 10 is preferably of the type which em-

ployes a plurality of relatively small diameter reactor tubes containing the desired catalyst, the tubes being confined within an enclosed zone to which heat from an external source may be supplied for the purpose of maintaining the reactants at the desired temperature during the conversion reaction. In addition, since relatively short periods of operation are employed in catalytic cracking because of the rather rapid deposition of carbon upon the surface and within the pores of the catalyst particles which necessitates frequent reactivation, it is preferred that a plurality of reactors be employed, although only one is shown in the drawing, in order that one or more may be segregated and the catalysts disposed therein subjected to reactivation while conversion of the hydrocarbon vapors is being accomplished in the other or others. Suitable means, not shown, may be employed for reactivating the catalyst disposed within the various reactors during the period those particular reactors are segregated from the balance for the purpose of reactivation.

Although the reactor described above constitutes the preferred type of reactor, it is not intended that the invention should be limited in this respect, for various other types of reactors, known to those in the art, may be substituted therefor without departing from the broad scope of the invention.

The conversion products leaving reactor 50 are directed through line 51 and valve 52 into separating zone 54, which forms the lower portion of fractionator and separator 53 which is operated at a superatmospheric pressure substantially the same as that employed on the outlet of reactor 50, wherein the vaporous conversion products are separated from the non-vaporous liquid residue. The non-vaporous liquid residue is removed from this zone through line 55 and valve 56 and recovered as a product of the process. The vaporous conversion products are directed through separating tray 57 into fractionating zone 58 where they undergo fractionation to form reflux condensate and to separate gasoline boiling range hydrocarbons. The reflux condensate formed in fractionating zone 58 is directed therefrom through line 59 and valve 60 to pump 61, which discharges through line 62 and valve 63 into line 44, wherein the reflux condensate commingles with the light oil, as previously described.

The gasoline boiling range hydrocarbons separated in fractionating zone 58 are directed in the vapor state from the upper portion thereof through line 64 and valve 65 into cooler and condenser 66 where they are subjected to cooling and condensation. The resulting distillate, together with undissolved and uncondensed normally gaseous hydrocarbons leaving condenser 66, is directed through line 67 and valve 68 into receiver 69 wherein the distillate and gas is collected and separated. The normally gaseous hydrocarbons collected in the upper portion of receiver 69 are directed therefrom through line 70 and valve 71 to storage or to further treatment as desired. A portion of the distillate collected in receiver 69 may be returned to the upper portion of fractionating zone 58, by well known means not shown, as a refluxing and cooling medium. The balance of the distillate may, when desired, be recovered as a product of the process by removing the same through line 72 and valve 73. The preferred procedure, however, is to subject the distillate recovered from

the high temperature cracking treatment to low temperature catalytic cracking treatment, in which case the distillate collected in receiver 69 is directed through line 74 and valve 75 to pump 76, which discharges through line 77 and valve 78 into line 82, the distillate thereafter being subjected to treatment as subsequently described.

Light reflux condensate formed in fractionator 18 is directed through line 79 and valve 80 to pump 81, which discharges through line 82 and valve 83. Reflux condensate in line 82 commingles with either the fractionated vapors or distillate from the thermal cracking treatment and/or the distillate from the high temperature catalytic cracking treatment after which the mixture is introduced to heating coil 84. The oil introduced to heating coil 84 is raised to a temperature in the range of 600 to 900° F. without substantial pyrolytic cracking thereof by means of heat supplied from furnace 85. The heated oil leaving heating coil 84 at a pressure ranging, for example, from substantially atmospheric to 200 pounds or more per square inch is directed through line 86 and valve 87 into reactor 89 wherein it is subjected to contact with a cracking catalyst while maintaining the oil at substantially the same temperature as that employed on the outlet of heating coil 84. The catalyst employed in reactor 89 may be of the same composition as that employed and described in connection with reactor 50. The low and high temperature cracking reactions differ essentially with respect to temperature and contact times employed, the reaction in reactor 50 being carried out at a relatively high temperature and short contact time, whereas the reaction in reactor 89 is carried out at a lower temperature and at a longer contact time. Reactors 50 and 89 may be of essentially the same design, however, as was previously mentioned, various other types of reactors may be employed to accomplish the desired results.

The conversion products leaving reactor 89 are directed through line 90 and valve 91 into fractionator 92, maintained at substantially the same or at a relatively reduced pressure relative to that employed on the outlet of reactor 89, wherein fractionated vapors boiling in the range of gasoline are separated from the higher boiling hydrocarbons, the latter being condensed as reflux condensate in the fractionating zone. The reflux condensate is removed from fractionator 92 and is directed through line 93 and valve 94 into pump 95, which discharges through line 96 and valve 97 into line 62 wherein the reflux condensate from this operation commingles with the reflux condensate from the high temperature cracking treatment and this mixture thereafter commingled with the charging oil and subjected to treatment, as previously described.

The fractionated vapors separated in fractionator 92 are directed from the upper portion thereof through line 98 and valve 99 into condenser 100 wherein they are subjected to cooling and condensation. The resulting distillate, together with undissolved and uncondensed normally gaseous hydrocarbons leaving condenser 100, is directed through line 101 and valve 102 into receiver 103 wherein the distillate and gas is collected and separated. The normally gaseous hydrocarbons collected in receiver 103 are directed from the upper portion thereof through line 104 and valve 105 and recovered as a product of the process. Distillate collected and separated

in receiver 103 is removed therefrom through line 106 and valve 107 and recovered as a product of the process.

As an example of one specific operation of the process as it may be conducted in an apparatus such as illustrated and above described to accomplish the desired results is approximately as follows:

A Mid-Continent reduced crude oil, having a 25° A. P. I. gravity, was commingled with heavy reflux condensate formed in the thermal cracking treatment and the mixture subjected to thermal cracking treatment in a heating coil and communicating reaction chamber operated at a temperature of 930° F. and a superatmospheric pressure of 250 pounds per square inch. The vaporous and liquid conversion products leaving the reaction chamber were introduced to the vaporizing and separating chamber operated at a superatmospheric pressure of 75 pounds per square inch, the vaporous conversion products separated from the non-vaporous liquid residue, and the latter recovered as a product of the process. The vaporous conversion products were subjected to fractionation at a superatmospheric pressure substantially the same as that employed in the vaporizing and separating chamber to form light and heavy reflux condensate and to separate gasoline boiling range hydrocarbons having an end boiling point of 400° F. The heavy reflux condensate was returned to the thermal cracking treatment.

The fractionated vapors from the thermal cracking treatment and the distillate formed in the high temperature catalytic cracking treatment, as hereinafter described, were commingled with the light reflux condensate from the thermal cracking treatment and the mixture heated to a temperature of 750° F. and passed over a silica-alumina-zirconia catalyst at a superatmospheric pressure of 100 pounds per square inch and a liquid space velocity of 1 in a low temperature cracking zone. The conversion products from the low temperature cracking zone were subjected to fractionation to separate fractionated vapors having an end boiling point of 300° F. from the higher boiling hydrocarbons. The fractionated vapors were subjected to cooling and condensation and the resulting distillate and gases collected and separated and recovered as products of the process.

The hydrocarbons, heavier than gasoline, separated in the fractionating zone following the low temperature cracking zone, were condensed as reflux condensate. This reflux condensate was commingled with reflux condensate produced in the high temperature catalytic cracking treatment and with a Mid-Continent gas-oil of 36° A. P. I. gravity. This mixture was vaporized and heated to a temperature of 940° F. and subjected to contact with a silica-alumina-zirconia catalyst at a superatmospheric pressure of 60 pounds per square inch and at a liquid space velocity of 4. The conversion products from this treatment were introduced to a separating zone wherein the vaporous conversion products were separated from the non-vaporous liquid residue and the latter recovered as a product of the process. The vaporous conversion products were subjected to fractionation to form reflux condensate which was subjected to treatment, as aforementioned, to separate fractionated vapors having an end boiling point of 400° F. The fractionated vapors from this treatment were condensed and the resulting distillate commingled

with the fractionated vapors from the thermal cracking treatment and light reflux condensate, as aforementioned.

The yield from this operation based on a feed of 50% reduced crude, and 50% gas-oil, was 60% of 300 end point gasoline having an octane rating of 78, a bromine number of 8, and an octane rating of approximately 90 after the addition of 6 cc. of tetraethyl lead. In addition, approximately 20% of non-vaporous liquid residue was obtained having an A. P. I. gravity of 10, the balance being attributable to gas and loss.

I claim as my invention:

1. A hydrocarbon oil conversion process which comprises thermally cracking a heavy hydrocarbon oil, catalytically cracking a lighter hydrocarbon oil, separating a light reflux condensate heavier than gasoline from the vapors produced by the thermal cracking of said heavy oil, commingling said light reflux condensate and gasoline products of both said cracking treatments, subjecting the resultant mixture to the action of a cracking catalyst at a temperature in the approximate range of 600 to 900° F. for a contact time adequate to effect a substantial transfer of

hydrogen from said reflux condensate to gasoline boiling olefins present in said mixture, whereby to produce a more saturated gasoline, and recovering the more saturated gasoline thus produced.

5 2. A hydrocarbon oil conversion process which comprises thermally cracking a heavy hydrocarbon oil, catalytically cracking a lighter hydrocarbon oil, fractionating the vapors resulting from said thermal cracking to separate relatively heavy and light reflux condensates therefrom, returning the heavier reflux condensate to the thermal cracking step, commingling said light reflux condensate and gasoline products of both 15 said cracking treatments, subjecting the resultant mixture to the action of a cracking catalyst at a temperature in the approximate range of 600 to 900° F. for a contact time adequate to effect a substantial transfer of hydrogen from said reflux condensate to gasoline boiling olefins present in said mixture, whereby to produce a more saturated gasoline, and recovering the more saturated gasoline thus produced.

EDWIN H. McGREW.
